UNITED STATES PATENT OFFICE.

MICHAEL HASCSÁK, OF NEW YORK, N. Y.

DERAILMENT-GUARD.

1,123,284.

Specification of Letters Patent.

Patented Jan. 5, 1915.

Application filed November 19, 1913. Serial No. 801,880.

To all whom it may concern:

Be it known that I, MICHAEL HASCSÁK, a subject of the King of Hungary, residing at New York, in the county of New York and State of New York, have invented certain new and useful Improvements in Derailment-Guards, of which the following is a specification.

This invention relates to derailment guards for railway rolling stock.

The primary object of the invention, is to provide an apparatus adapted to be carried by the engine and, if preferred, by each of the cars, which, in the event of the engine or a car starting to jump the track, will be rendered operable to grip the track and thus prevent a catastrophe.

With the above and other objects in view, as will appear as the nature of the invention is better understood, the same consists in the novel construction and combination of parts of a signaling device for railway trains, as will be hereinafter fully described and claimed.

In the accompanying drawings forming a part of this specification, and in which like characters of reference indicate corresponding parts:—Figure 1 is a view in perspective of a locomotive, showing the same equipped with the improvement of the present invention. Fig. 2 is a view in side elevation showing the apparatus in gripped or locked position relative to a railway track. Fig. 3 is a similar view, partially in section, displaying the normal position of the track gripping jaws. Fig. 4 is a view in end elevation of the structures shown in Figs. 2 and 3. Fig. 5 is a view in side elevation, partly in section, showing an electrical means for releasing the locking jaws. Fig. 6 is a fragmentary detail view, partly in section, showing the manner in which the two track gripping jaws are held in open position. Fig. 7 is a view in side elevation, on an enlarged scale, of the trip mechanism for releasing the gripping jaws shown in Figs. 1—4.

Referring to the drawings, and to Fig. 1 thereof, T designates a portion of the truck of a locomotive to which is secured a housing or casing 1 supporting and containing the operating mechanism controlling the release of the track gripping jaws. These latter are designated 2 and 3, and are mounted upon a common pivot 4 extending through the casing. Each jaw is a counterpart of the other, and is connected by an ordinary

plier joint as shown in Fig. 3. Each of the jaws is provided with a nose 6 pivotally connected to the jaw by recessing the latter and the nose to form lugs 6^a having perforations 60 through which a pin 7 extends surrounded by a coil spring 9 one end of which bears against the jaw and the opposite end against the nose 6, to permit the latter to have a pivotal movement against the tension of the 65 spring.

The jaws 2 and 3 are each reinforced by a strap 2^a, said straps having a plier-joint connection as at 2^b at their upper ends, and formed with aligned openings to receive the 70 projecting end of the pivot 4, and secured at their lower ends to the jaws by pivot bolts 4^a.

While it is desirable to provide the yieldable pivoted nose 6 for each of the jaws, the manner of attaching the nose is not restricted to the pin and spring device shown.

Each jaw is provided with a lug 10 to which is secured one end of a coiled spring 11, the other end of which is secured to the casing 1. The function of these springs 11 80 is to project the jaws to closed position, as shown in Fig. 2 when a latch 12 arranged within the casing is released, the latch being provided with longitudinal slots 13 indicated by dotted lines in Fig. 3 through which pass 85 bolts 14 that serve to hold the latch combined with the casing and at the same time have sliding movement relative thereto. The lower end of the latch has a reduced extension 15 that is designed to enter seats 16 in 90 the opposed faces of the jaws above their pivotal point as clearly shown in Fig. 6.

The means for actuating the latch to release the jaws comprises a trip bar 17, the upper portion of which is provided with two 95 longitudinal slots 18 through which pass pins or bolts 19 that serve to secure the trip to the casing. Adjacent to its lower end, the trip has an off-set extension 20, the lower end of which is combined in any suitable 100 manner with a wheel 21 having a flange 22 that is designed to travel under the lower side of the tread of the rail R. That portion of the trip carrying the wheel is hinged to the adjacent portion at 23 and is normally 105 held in the position shown in Fig. 4 by a spring 24, the object of the joint between the two members of the trip being to permit the wheel carrying portion to yield should it strike an obstruction, such as a fish plate, 110 and thus prevent injury to the trip. To the upper end of the trip is secured an eye 25

in which is secured one end of a rope or chain 26 that passes around a sheave 27 journaled in the casing and is secured at its other end to a pin 28 projecting from the upper end of the latch.

Secured to the inner end of the jaw 3 is an eye 29 to which is secured one end of a rope or chain 30 which passes upward through the casing through an opening in the running board B of the locomotive, through an opening in the front wall of the cab C and is secured to a lever 31 mounted in the latter.

The operation of the structure thus far described is as follows: Assuming the parts of the apparatus to be in the position shown in Fig. 3, and the engine starts to jump the track, the flange 22 of the wheel 21 will engage with the under side of the tread of the rail, thereby exerting a downward pull upon the trip 17 which will cause an upward lift, through the medium of the rope 26, of the latch 12, thereby withdrawing its reduced end 15 out of engagement with the seats 16 in the jaws, thus releasing the latter whereupon the jaws will instantly grip the rail, the downward movement of the jaws exerting a pull upon the cable 30 which will cause the lever 31 to sound a gong 32, and this will notify the engineer that the gripping jaws are in engagement with the track whereupon he will immediately stop his engine, and again set the jaws.

Should it be desired to adapt the trip 17 to be manipulated by the engineer, and which would be of advantage, a cable 33 may be connected with the upper end of the latch 12 and be attached at its other end to the lever 31.

In addition to the two operations above described, the latch may be operated electrically, as shown in Fig. 5. This consists in connecting with the upper end of the latch 12 the core 34 of a solenoid magnet 35, with which connects a circuit composed of conductors 36 and 37 including a battery 38. These conductors lead to two contacts 39 and 40 carried by a plate 41 forming an extension of a disk 42 that is secured to any appropriate portion of the truck of the locomotive. Pivoted upon this disk and intermediate of its ends is an arm 43 having at one end a nose 44 arranged to be disposed under the tread of the rail, and at its other end with a switch 45. In order to maintain the arm normally out of engagement at its nose with the rail, a helical spring 46 is employed, one terminal of which is secured to the disk 42 and the other to the arm between the nose end and the pivot.

In order to convey a signal to the engineer, there are tapped into the conductors 36 and 37, two other conductors 47 and 48 that lead to a bell or other suitable signal in the cab.

In operation should the nose of the arm 43 contact with the under side of the tread of the rail, the outer end of the arm will be raised, bringing the contacts 39 and 40 into electrical connection through the switch 45, thereby completing the circuit to the magnet 35, whereupon the core 34 will be energized and lift the latch out of engagement with the seats in the jaws, and at the same time transmitting a signal to the engineer.

From the foregoing description, it will be seen that although the improvements of this invention are simple in character, that they will be thoroughly efficient for the purposes designed and will coöperate in a certain and practical manner to secure the objects sought.

What I claim as new and desire to secure by Letters Patent is:—

1. A device of the character described comprising a pair of rail gripping jaws, means for normally maintaining the jaws out of engagement with the rail, and means actuated by the lifting of the locomotive carrying the device automatically to release the jaws to permit them to grip the opposite sides of the tread of a rail.

2. A device of the character described comprising a casing secured to the truck of an engine, a pair of jaws pivoted to the lower end of the casing and having rail tread engaging seats, springs connecting the jaws and the casing, means for holding the jaws open against the tension of the springs, and means for releasing the jaws upon upward movement of the engine.

3. A device of the character described comprising a casing arranged to be secured to the truck of an engine, a pair of jaws pivotally connected to the lower end of the casing and having rail engaging seats terminating in spring-pressed noses, springs connecting the jaws and the casing, a latch arranged within the casing and having a part to interlock with the jaws to hold the same open against the tension of the spring, a vertically slideable trip flexibly connected with the latch, and a wheel carried by the lower end of the trip and having a flange disposed beneath the rail tread.

4. A device of the character described comprising a casing secured to the truck of an engine, a pair of jaws pivoted to the lower end of the casing and having rail tread engaging seats, the outer ends of the jaws terminating in pivoted noses, springs connecting the jaws and the casing, means for holding the jaws open against the tension of the springs, and means for releasing the jaws upon jumping of the engine.

5. A device of the character described comprising a pair of rail gripping jaws, means for normally maintaining the jaws out of engagement with a rail, and means operating automatically by the jumping of

a locomotive or car carrying the device to release the jaws to permit them to pass around each side of the tread of a rail.

6. A device of the character described, comprising a pair of rail-gripping jaws, means for normally maintaining said jaws out of engagement with a rail and under spring tension, and means operable automatically by the jumping of a locomotive or car for releasing said jaws to permit

them to grip the rail.

7. The combination with a supporting truck, of a casing or housing, a pair of spring-controlled rail-gripping jaws normally held under spring tension away from a rail, and a latch within said housing for

holding said jaws apart, and means for releasing said latch when the truck moves to jump the rail.

8. A safety device for railway rolling stock, comprising a pair of rail-gripping jaws, means for maintaining said jaws under spring tension away from the sides of a rail, and means operable by the upward movement of the truck to release said jaws maintaining means.

In testimony whereof I affix my signature in presence of two witnesses.

MICHAEL HASCSÁK.
